UNITED STATES PATENT OFFICE.

JOHN F. CHASE, OF AUGUSTA, MAINE.

CONDENSING APPARATUS.

SPECIFICATION forming part of Letters Patent No. 396,539, dated January 22, 1889.

Application filed October 31, 1888. Serial No. 289,646. (No model.)

To all whom it may concern:

Be it known that I, JOHN F. CHASE, a citizen of the United States, residing at Augusta, in the county of Kennebec and State of Maine, 5 have invented certain new and useful Improvements in Condensing Apparatus; and I do hereby declare the following to be a full, clear, and exact description of the invention, such as will enable others skilled in the art to 10 which it appertains to make and use the same.

This invention relates to condensers of that class known as "fresh-water" condensers, and it has for its object to provide a simple, effective, and inexpensive apparatus for household 15 or domestic use in which a large condensing-surface is provided in a small compass; and it consists of the parts and combinations of parts hereinafter described and claimed.

In the accompanying drawings, forming a 20 part of this specification, Figure 1 is a perspective view of my improved apparatus; Fig. 2, a vertical longitudinal section through the same; Fig. 3, a perspective view of a modification of one of the condensing-chambers, and 25 Fig. 4 a section through the same.

Similar letters refer to similar parts throughout the several views.

A represents a metallic pipe of any desired 30 diameter, one end of which is suitably connected with a steam-generator (not shown) of any desired kind, the utensil known as a "teakettle" answering the purpose excellently.

To the pipe A a pipe, B, is connected at 35 right angles, and has its lower end fitted in a collar, a, which projects from the center of a supply-tube, C, said tube being closed at both ends, and having a series of lips, b, projecting from its under side at regular intervals apart from end to end of the tube, to which the short 40 tubes c, which project from the edges or peripheries of the disk-shaped condensing-chambers D, are connected. The chambers D are formed of circular concavo-convex plates of thin metal joined together at their edges in 45 any suitable manner, with their concave faces toward each other, so as to form a condensing-chamber between them whose greatest width is at the center, and which tapers gradually from the center to the peripheries of the 50 plates. In Figs. 1 and 2 these plates are shown

as perfectly smooth plane surfaces; but they may be corrugated from the center toward the edge or periphery, if desired, as shown in Figs. 3 and 4, in which the corrugations h are shown as deepest at the center of the plate 55 and gradually decreasing in depth to near the periphery, where they terminate or merge in the metal of the plate.

In the lower edges of the chambers D opposite the tubes c tubes d are secured or formed, 60 which enter lips or collars n, formed on the upper side of a large receiving-tube, F, in which the water of condensation is received. This tube is closed at both ends and has a spigot, E, or other means for drawing off the 65 water provided. The tube F rests on a support formed with the semicircular collars p, having perforated lugs r formed thereon, in which the bent ends of legs s are inserted. To the collars p side boards, t, which extend 70 along the tube F on each side and form a support for the chambers D, are riveted or otherwise secured.

The metal out of which the plates are made must be very thin in order to secure the best 75 results, and therefore, if made perfectly flat in the shape of disks and joined together at the edges, would not be strong enough to resist even slight pressure or blows accidentally or otherwise applied thereto, but would give 80 to the pressure or blow and become bent, thus injuring and perhaps closing the free passage between the plates and ruining the apparatus. Therefore, in order to give the required strength without a corresponding 85 thickening of the metal, I make the plates concavo-convex, as described above, leaving, however, only a narrow or contracted passage between them which at its widest point is not over one and one-half inch. The corruga- 90 tions in the plates are also very close together when the plates are brought together, so that at the widest point it will not be over the dimension named.

In operation the steam or vapor enters the 95 pipes A and B, and from thence into the tubes C, from which it escapes through the tubes c into the chambers D, where it is condensed by coming in contact with the plates forming the chambers, said plates being of thin metal, 100

which quickly cools, and the water of condensation escaping from said chambers through tubes *d* into the receiving-tube *F*, from which it may be drawn by the spigot or other suitable means. Substantially the same operation takes place when the chambers shown in Figs. 3 and 4 are employed, the only reason for their employment being the greater cooling-surface they afford, owing to the plates 10 forming the same being corrugated, as described.

Having thus described my invention, what I claim as new, and desire to secure by Letters Patent, is—

15 1. The combination, in a condensing apparatus, of the pipes *A* *B*, the tube *C*, centrally connected with said pipe *B* and having a series of lips formed on one side thereof, the series of disk-shaped condensing-chambers 20 formed of the concavo-convex plates joined

at their peripheries connected to said lips, the receiving-tube having a series of lips on one side connected with said condensing-chambers, and means for supporting said receiving-tube, substantially as described. 25

2. The combination, in a condensing apparatus, of the pipes *A* *B*, the tube *C*, connected with said pipe *B*, a series of upright condensing-chambers formed by the disk-shaped concavo-convex plates having the tapering corrugations therein, and the receiving-tube communicating with said chambers, substantially as described. 30

In testimony whereof I affix my signature in presence of two witnesses.

JOHN F. CHASE.
